UNITED STATES PATENT OFFICE.

FRANCISQUE DUMOND AND CLÉMENT GALVIN, OF LYON, FRANCE.

HYDROGLIDER.

Application filed October 5, 1921. Serial No. 505,522.

To all whom it may concern:

Be it known that we, FRANCISQUE DUMOND, of Lyon, and CLÉMENT GALVIN, of Lyon, France, citizens of the French Republic, have invented certain new and useful Improvements in Hydrogliders, of which the following is a specification.

The present invention relates to improvements in hydro-gliders, for the purpose of 10 avoiding suction of the water, and to ensure the stability of the hull whilst increasing the gliding properties of the device particularly when navigating on rough water.

These results are obtained by the shape 15 and proportions given to the hull of which the lower face is provided with a slight set-back and is in communication with the atmosphere by air conduits the lower orifices of which are immediately behind said set-back.

In order to give the device sufficient rigidity the hull is provided with two longitudinal carlines forming an undistortable beam capable of resisting the combined 25 pressures of water and air at any rate of speed.

The annexed drawing illustrates an example of construction of the improved hydro-glider.

30 Figs. 1 and 1^a are longitudinal sections thereof on line 1—1 of Fig. 2.

Fig. 2 a cross section on line 2—2 of Fig. 1 and

Figs. 3 and 3^a plan views.

35 Fig. 4 is a section on line 4—4 of Fig. 1.

The keel or hull comprises:—1. A front part A—B of which the nose forming the bow of the vessel is only immersed when travelling over waves, if there are any, 40 and acts to throw them sideways. This part A—B extends more than a third of the whole length of the hull and its inclination in relation to the line of flotation is at an angle of from two to five degrees.

45 2. Two gliding surfaces *a* one on each side of the vessel built in with the part A—B above the line of flotation and acting as a bearing surface in all stages of progress from starting to full speed, when it 50 only directs the streams of water downwards.

3. A rear surface B—C rising slightly from B to C in relation to the line of flotation, so that the molecules of water sliding 55 downwards resume their equilibrium by producing a natural wave above the static

level of the said surface. The length B—C is such that the hull receives the reaction from bottom to top of this wave, which reaction dresses the vessel during motion as 60 otherwise it would have a tendency to sink at the stern. This unusual lengthening of the rear part B—C ensures longitudinal stability of travel and allows the employment of efficient rudders of which one *d* is 65 immersed in the water and one or two others *e* act in the air. In practice, it is advisable for the length B—C to be at least equal to twenty-five times the depth of immersion of the hull from the line of flotation at B. 70

The bottom of the hull has, in a transverse plane passing through B, a slight set-back *b* about five millimetres in height, immediately behind which are the orifices of two conduits *c* communicating at their upper 75 ends with the atmosphere. Air is thus conveyed beneath the hull at atmospheric pressure, for the sole purpose of avoiding suction of the water, which without such provision would be produced behind the set 80 back *b*. The slight height given to the set-back *b* is just sufficient to cause the streams of water to lose adherence with the surface of the hull behind the set-back and which is in communication with the atmosphere in 85 the manner described. This set-back therefore performs a function quite different from the very accentuated set-backs hitherto provided in certain hydro-gliders.

Owing to the arrangement of this slight 90 set-back *b* and the air conducting conduits *c* great facility of gliding is obtained, even with the wind ahead and in rough water and also a distinct improvement in the longitudinal stability of the vessel is obtained, 95 any suction even partial such as might occur when tacking or at meeting cross currents, being prevented by this arrangement.

In order to give the hydro-glider the necessary rigidity, its hull is provided with two 100 carlines *f* supported and strengthened by tie-beams *h* these carlines being extended upwards as at *g*.

The hydro-glider is completed by an air propeller *i* and by the necessary accessories 105 which do not enter into the scope of the present invention.

What we claim as our invention and desire to secure by Letters Patent of the United States is:—

110 In a hydro-glider, a hull having a front part forming the bow thereof and a rear

part of rectangular shape in plan and of a length considerably greater than said front part the base of said front part being upwardly inclined towards the bow from two to five degrees with respect to the horizontal and the base of the rear part being upwardly inclined towards the stern of said hull to a lesser degree than the base of said front part a single transverse set back of slight depth extending along the line of intersection of said front and rear parts said line of intersection being in front of the centre of gravity of the hull, two hydro-planing surfaces one on each

side of said front part, conduits the upper ends of which are in communication with the atmosphere and the lower outlets are immediately behind said set back and an aerial propeller for driving the hydroglider.

In witness whereof we have signed this 20 specification in the presence of two witnesses.

FRANCISQUE DUMOND.
CLÉMENT GALVIN.
